STOPPER OR SIMILAR ARTICLE

Roy E. Stroup, St. Joseph County, Ind.

Application August 8, 1955, Serial No. 37,374

Term of patent 7 years

(Cl. D58—10)

Fig. 3.

Fig. 2.

Fig. 1.

Fig. 4.

Fig. 5.

I claim:

The ornamental design for a stopper or similar article, as shown.
